United States Patent Office

Des. 232,666

Patented Sept. 3, 1974

232,666

HOLDER FOR UMBRELLAS

Brower C. Spransy, 4516 Rynex Drive, Alexandria, Va.
22312, and George B. Spransy, 18 Dog Wood Acre,
Chapel Hill, N.C. 27514

Filed Oct. 12, 1972, Ser. No. 297,044

Term of patent 14 years

Int. Cl. D3—02
U.S. Cl. D87—1 R

The sole figure is a perspective view of a holder for umbrellas showing our new design.

The broken lines showing a suitcase and an umbrella are for illustrative purposes only.

We claim:

The ornamental design for a holder for umbrellas, as shown and described.
